THE NORRIS PETERS CO., PHOTO-LITHO., WASHINGTON, D. C.

UNITED STATES PATENT OFFICE.

THEODORE MILLER, OF NEW YORK, N. Y.

STEAM-GENERATOR.

SPECIFICATION forming part of Letters Patent No. 664,881, dated January 1, 1901.

Original application filed January 25, 1900, Serial No. 2,714. Divided and this application filed March 27, 1900. Serial No. 10,336. (No model.)

To all whom it may concern:

Be it known that I, THEODORE MILLER, a citizen of the United States, and a resident of New York city, county and State of New York, 5 have invented certain new and useful Improvements in Steam-Generators, of which the following is a specification.

This invention relates to an improved steam-generator, and particularly to means 10 whereby the heat admitted to the shell of the boiler, which contains the steam-generating tubes, may be accurately controlled, the present case being a divisional application of the one filed January 25, 1900, under Serial No. 15 2,714.

In the accompanying drawings, Figure 1 is a vertical central section, partly in elevation, of my steam-generator. Fig. 2 is a vertical section through the lower part of the same, 20 showing the damper in a different position; and Fig. 3, a horizontal section on line 3 3, Fig. 1.

The letter *a* represents the shell of the generator, within which is contained a coiled tube *b* or a series of communicating tubes, within 25 which the steam is generated. This tube communicates at one end with the feed-water pipe *c*, while at its other end the steam generated is carried to the engine by pipe *d*, having pressure-gage *d'* and blow-off cock *d''*.

The generator may be heated in any manner desired, the fire-chamber or source of heat *h* being arranged below the shell *a*. The shell is separated from the fire-chamber by a 35 perforated register composed of two perforated plates *e f*, of which one—say the upper plate *e*—is rotatable to constitute a damper, while the lower plate *f* forms a perforated bottom that extends underneath the entire shell 40 *a*, and thus constitutes a perforated partition between the steam-generating chamber and the fire-chamber.

The damper has a perforated extension *e'* projecting over a perforated side *f'* of the fire-chamber, that communicates with a bypass flue *g*. The arrangement of perforations is such that when heat is admitted from the fire-chamber to the shell *a* the flue *g* is 45 shut off, and vice versa.

50 The damper *e* is operated by a handle *e''*,

which likewise controls the blow-off cock *d''* by elbow-lever *e''*, link *e''*, and lever *e''* in such a manner that the cock is closed when the heat is directed into the shell *a* and opened when the heat is directed into the flue *g*. 55

To start the generator, the fireplace is first put in communication with the flue *g* to obtain a good draft and to indirectly warm up the generator-coil *b* by the heat radiated or conducted through the closed register-plates 60 *e* and *f*, and then the damper *e* is turned to disconnect the flue and to direct the heat into the shell *a*, so as to thoroughly heat the tube *b*. In this way the gases of combustion are brought into contact with the generator-tube 65 *b* only after the latter has been well heated, and thereby the condensation of moisture and the precipitation of soot on the generator-tube *b* are prevented. When no steam is required for any length of time, the damper *e* is turned, 70 so as to shut off the heat from the shell *a* and deflect it into the flue *g*, while simultaneously the blow-off cock *d''* is opened, whereby the boiler is relieved entirely of steam-pressure and danger of explosion is avoided. 75

It will be seen that in my improved generator the heat admitted to the shell may be accurately controlled and that by properly setting the damper the heat or any excess thereof may be deflected into the flue *g*. 80

What I claim is—

A steam-generator composed of a steam-generating chamber having a perforated bottom, a fire-chamber adapted to communicate with said steam-chamber through said bottom, a bypass flue, a perforated wall between fire-chamber and flue, and a perforated damper that extends over the perforated bottom and over the perforated wall, said damper being adapted to direct the heat either into the generating-chamber or into the flue, substantially as specified. 85 90

Signed by me at New York city, county and State of New York, this 26th day of March, 1900.

THEODORE MILLER.
